Specification for Design.

Patented May 31, 1921.

Application filed May 21, 1920. Serial No. 383,290. Term of patent 14 years.

To all whom it may concern:

Be it known that I, DAYTON A. DOYLE, Jr., a citizen of the United States, residing at Akron, in the county of Summit and State of Ohio, have invented a new, original, and ornamental Design for Elastic Vehicle-Tires, of which the following is a specification, reference being had to the accompanying drawings, forming a part thereof.

Figure 1 is a plan view of a portion of an elastic vehicle tire, showing my new design, and,

Fig. 2 is a transverse sectional view of same taken on line 2—2 of Fig. 1.

I claim:

The ornamental design for an elastic vehicle tire as shown.
